UNITED STATES PATENT OFFICE

1,939,031

MOTION PICTURE APPARATUS

Christian Aalborg, Pittsburgh, and Frank Conrad, Wilkinsburg, Pa., assignors to Westinghouse Electric and Manufacturing Company, a corporation of Pennsylvania

Application May 1, 1930. Serial No. 449,023

3 Claims. (Cl. 88—16.2)

Our invention relates to acousto-cinematographic apparatus wherein the sound is reproduced from a wax record and it has particular relation to domestic equipments of this type.

5 Although domestic apparatus is designed chiefly for the reproduction of a sound record in synchronism with the projection of a motion-picture film, it may be put to a number of uses that, from the stand-point of the individual using the apparatus, are at least as important as its primary use.

As is well known, a large percentage of the amateur films distributed at the present time are not provided with sound records synchronized therewith. Furthermore, by reason of the obvious difficulties involved, it is unlikely that, in the near future, amateurs will be provided with facilities for producing synchronized sound pictures. On the other hand, in the past, one of the most 20 tempting features of the domestic motion-picture equipment, from the stand-point of the consumer, has been its adaptability to the projection of films which he has photographed.

From a commercial standpoint, it is, therefore, 25 imperative that provision be made for operating the projection system alone.

It is to be noted, however, that, with amateur cameras now generally available, the exposures are made at the rate of 16 per second, while, in 30 view of the necessity for constancy of speed, pictures synchronized with sound are projected at the rate of 24 per second. Since the illusion of continuity is completely preserved at a projection rate of 16 pictures, projection at a higher rate 35 represents a costly waste in film and unnecessary film-processing. Moreover, a picture that is photographed at one speed and projected at a greater speed has a ludicrous and unreal appearance on the screen.

40 As a consequence, it is necessary, in providing for the independent projection of a picture by a machine designed to project a picture with synchronized sound, that provision be made for projecting the silent picture at a slower rate than that at which sound pictures are projected.

Since many desirable pictures are not equipped with synchronized sound records, the owner of a machine may desire to reproduce the sound from an ordinary record while he is projecting a silent picture. In this connection, attention is called to the fact that, while the 16"-diameter record, 50 synchronized with a picture projected at a rate of 24 frames per second, rotates at an angular velocity of 33 revolutions per minute, the ordinary

domestic 12"-diameter record rotates at a rate of 78 revolutions per minute.

Provision must, therefore, be made, in the apparatus, for reproducing the sound and projecting the picture simultaneously but independently, 60 the former at a velocity of 78 revolutions per minute, and the latter at a rate of 16 frames per second.

Finally, a feature that makes the machine particularly desirable to a purchaser is the possibility of using it as a phonograph. The provision of equipment for operating a sound record alone is, therefore, essential for the commercial success of the apparatus.

It is needless to say that it is indispensable that 70 domestic apparatus having such diverse applicability, shall be simple in its structure and in its manipulation, and silent in its operation.

In acoustic-cinematographic apparatus constructed according to the teachings of the prior 75 art, with which we are familiar, no provision is made for taking advantage of the wide range of usefulness of equipment of this character.

It is, accordingly, an object of our invention to provide acousto-cinematographic apparatus that 80 shall be simple in structure, silent in operation and of so tractable a character that it shall have an extensive range of usefulness.

A further object of our invention is to provide acousto-cinematographic apparatus that may, 85 with facility, be used as pure acoustic apparatus or as pure cinematographic apparatus.

Still another object of our invention is to provide apparatus for the projection of a picture and for the reproduction of sound at a plurality 90 of speeds.

More specifically stated, it is an object of our invention to provide acousto-cinematographic apparatus that may be used for the projection of a picture and the simultaneous reproduction of 95 sound synchronized therewith; for the projection of a picture alone; for the projection of a picture and the simultaneous reproduction of sound not synchronized therewith and for the reproduction of sound alone.

According to our invention, we provide acousto-cinematographic equipment with a plurality of dentate and frictional power-transmission mechanisms that may be so interlinked by the operator of the machine that any desired combination 105 of elements of the machine may be operated at their requisite speeds.

The novel features that we consider characteristic of our invention are set forth with particularity in the appended claims. The inven- 110

tion itself, however, both as to its organization and its method of operation, together with additional objects and advantages thereof, will best be understood from the following description of a specific embodiment, when read in connection with the accompanying drawings in which

Fig. 1 is a view, in side elevation, of an acousto-cinematographic machine showing the prime mover and the power-transmission mechanisms.

Fig. 2 is a view, in side elevation, of the operative parts of a gear-shift lever disposed in the machine.

Fig. 3 is a view, in front elevation, of the retaining parts of the gear-shift levers.

Fig. 4 is a view, in side elevation, of the machine showing the film-feeding and film-advancing mechanisms.

Fig. 5 is a view, in elevation, of the head of the machine, the projection-lens bracket and the cover for the intermittent movement being removed.

Fig. 6 is a view, in section, taken along line VI-VI of Fig. 5.

Fig. 7 is a view, in perspective, of the cam follower.

Fig. 8 is a view, in perspective, of a clamp whereby the cam follower is fastened to the claw supporting bar.

Fig. 9 is a view, in front elevation, of a film-advancing sprocket and its pad rollers.

Fig. 10 is a view, in side elevation, of the sprocket and its rollers.

Fig. 11 is a view, in perspective, of the film gate.

The apparatus shown in the drawings comprises a casting 1 provided with a plurality of supports 3 and having a plurality of cavities, 5, 7, 9, 11 and 13 located therein to receive a motor 15, and a plurality of worms 17, 19 and 21 and worm wheels 23, 25 and 27 and to contain a lubricating fluid.

A motor shaft or main drive shaft 29 is supported on a plurality of bearings 31 pressed into a horizontal channel 32 which connects the lower gear-wheel cavity 7 and the motor cavity 5. The lower worm 17 is centrally located on the motor shaft 29, while a pulley 33, equipped with a plurality of surfaces 35 and 37 to receive a flat belt 39, is disposed on one end thereof.

A vertical channel 41 is provided between the lower gear-wheel cavity 7 and the upper gear-wheel cavity 9 and, centrally located therein, is a shaft 43 the vertical thrust of which is supported by a ball 45 loosely mounted in the end of a bolt 47 that projects into the casting 1 and is fastened to it by a locknut 49. A turn-table 51, having a wax record 53 centrally located thereon, is pressed on the unsupported end of the shaft 43 and is keyed thereto.

The lower and upper worm gear-wheels 23 and 25 are disposed on the vertical shaft 43 between the thrust bearing 45 and the turn-table 51 and are rotatable relative to the shaft. The gear-wheels do not abut the channel 41 but are separated therefrom by shouldered metallic blocks 55 and 57 that are axial with the shaft 43 and rotatable relative thereto.

The upper gear-wheel 25 is prevented from sliding along the shaft under gravity by the engagement of the shoulders of the upper block 57 with the end of the channel 41 and a washer 59, supported on a nut 61 screwed on the lower end of the shaft 43, prevents the lower gear-wheel from sliding along the shaft.

The blocks 55 and 57 are of square cross sec-

tion but are equipped with buttons 63 and 65 of circular section that project into the channel 41. The buttons 63 and 65 have key slots 67 and 69 milled in their surfaces to engage keys 71 and 73 which are located on the end of a vertical hollow shaft 75 that is capable of sliding longitudinally along the vertical shaft 43 but is prevented from rotating relative thereto by the coaction of a pin 77 traversing the shaft 43 and a plurality of slots 79 milled along the shaft 75.

The gear-wheels 23 and 25 are linked with their associated blocks 55 and 57 through a plurality of flat springs 81 and 83 that engage the gear-wheel by means of a plurality of pins 85 and 87 projecting from their surfaces and are fastened to the blocks. The hollow shaft 75, when in engagement with the button 63 or the button 65, is thus rotated by the corresponding gear-wheel through a flexible coupling and, in turn, causes the vertical shaft 43 and the turn-table 51 attached thereto to rotate. It is to be noted that irregularities that exist in the rotational velocity of the worm gear-wheels 23 and 25, by reason of their tooth reaction with their corresponding worms 17 and 19, are prevented by the flexible couplings, from appearing in the rotation velocity of the turn-table.

A plurality of equally spaced horizontal grooves 89 are milled in the surface of the hollow shaft 75, and a pinion 91 of pitch equivalent to the spacing of the grooves 89, coacts with them to move the shaft 75 in an axial direction. The pinion 91 is rigidly supported on a shaft 93 that is, in turn, mounted in a horizontal channel traversing the casting in a direction perpendicular to the vertical plane determined by the drive shaft 29.

The shaft 93, supporting the pinion, is rigidly fastened, at one end, to a lever 95, and a shouldered stud 97 is provided for pivoting the lever 95 and for rotating the shaft attached thereto.

The stud 97 traverses a collar 99, fastened to the free end of the lever and its shoulders 101, abuts the unengaged edge thereof. It is equipped with a button 103 on one end and, adjacent to the button 103, a slotted washer 105 is located. A compression spring 107, disposed between the lever 95 and the washer 105, urges the stud 97 into engagement with the collar 99, at the same time causing the button 103 to latch in a groove 111 disposed in a plate 109, over which the operating stud 97 traces out its path, in a position corresponding to the natural position of the shaft.

A second lever 113 is centrally supported on the remaining end of the pinion shaft 93, and a tension spring 115 is anchored to a pin 117, fastened near one end of the lever, and to a pin 118 projecting from the main casting. The pins 117 and 118 are so disposed relative to each other that they are co-linear with the pinion-shaft center for the neutral position of the hollow shaft 75 and, consequently, the spring 115, is inactive in this position. However, in its two extreme positions, the hollow shaft is firmly held in engagement with the corresponding blocks by the action of the spring.

Power is transmitted from the lower shaft 29 to the upper shaft 119 through the flat belt 39 that is driven by the pulley 33 centrally mounted on the former shaft and drives a pulley 121 centrally supported on one end of the latter. As is shown in Fig. 1, the upper pulley 121 is provided with a plurality of surfaces 123 and 125 and the belt, which may be driven at a mul-

tiplicity of linear speeds from the lower pulley 33, may drive the upper shaft at a multiplicity of angular speeds. A belt tightener 127, rotatably mounted in a bracket 129 that is pivotally supported on a stud 131 projecting from the main casting, holds the belt under tension.

When the hollow shaft 75 engages the lower worm gear-wheel 23, the turn-table 51 is directly driven from the main shaft 29 at its higher speed.

10 If the belt 39 is, at the same time, removed from the driving pulley 33, the turn-table only is rotated.

On the other hand, when the hollow shaft 75 is in engagement with the upper worm gear-wheel 25, the turn-table 51 is rotated at its lower speed, that is, at the speed at which sound and pictures are synchronized. The power for this rotation is, however, transmitted from the drive shaft 29 to the upper shaft 119 through the belt.

20 Hence, when the turn-table 51 is rotated at its lower speed, the projection apparatus is necessarily active, for the upper horizontal shaft 119 transmits the necessary power for driving the projection apparatus, as will be hereinafter described.

It is, furthermore, seen from the above description that, when the belt 39 is in engagement with the pulleys, and the hollow shaft 75 is driven through the lower gear-wheel 23, the projection system and turn-table are operated independently. Moreover, when the hollow shaft 75 is in neutral position, and the belt 39 is in operative position, the projection apparatus only is operated. Finally, the projection apparatus is operated for sound pictures by the coaction of the belt 39 and the inner pulley surfaces 37 and 125, while it is operated for silent pictures by the coaction of the belt 39 and the outer pulley surfaces 35 and 123.

40 The projection system comprises a sprocket 133 serving as both feed and take-up sprocket, an intermittent, a picture gate and an optical projection system. These elements are mounted on what may be termed the projection head 135 of the casting. A tone arm 137 carrying a pick-up 139 at its end, is pivotally supported in an opening in the projection head 135.

The sprocket 133 is disposed on one end of a shaft 140 that is motivated from the upper shaft 119 through the worm 21 and the worm gear-wheel 27. It advances a film strip 141 from a feed-reel 143 into a loop reservoir 145 from which it is intermittently advanced, through a picture gate 147, into a second loop reservoir 149 by a plurality of claws 151. From the second loop, the film strip 141 is delivered, by the sprocket 133, to a take-up reel 153 that is rotated by the coaction of a belt 155, a drive pulley 157, situated near the remaining end of the sprocket shaft 140, and a driven pulley 161, situated on the take-up reel spindle 163. The loops 145 and 149 are separated from the mechanisms of the apparatus by a plurality of strips 165 fastened to the main casting.

65 The film 141 is held in engagement with the sprocket 133 by a multiplicity of rollers 167 mounted on a plurality of plates 169 provided with cam grooves 171. The plates are slidably supported in tracks 173 and are moved into and out of engagement with the sprocket by the coaction of the cam grooves 171 and a plurality of pins 175 projecting from an operating lever 177.

The intermittent movement comprises a cam disc 179 centrally situated on an end of the hori-

zontal shaft 119 and a cam follower 181 mounted adjacent to the disc 179.

The cam follower is composed of a bar of longitudinal T-section having a plurality of pins 183 and 185 disposed at the tips of its flanges and at the end of its stem, and having a rectangular slot 187 symmetrically milled relative to its long center line. The claws 151 are supported on an arm 189 extending approximately at right angles from a rod 191 that has, substantially centrally located on it, a section 193 of rectangular cross section which engages the cam follower 181 in the slot 187. The bar and cam follower are clamped together by a metallic block 195 of T-section that is secured to the latter.

The claws 151 are moved longitudinal to the film by reason of the translational motion induced in the rod 191 by the coaction of the pin 185, disposed in the stem of the cam follower 181, and a cam groove 197, milled in the cam disc 179. The motion of the claws transverse to the film arises from the pivoting motion induced in the rod 191 by the coaction of the remaining pins 183 with a surface cam 199, projecting from the face of the disc 179.

100 The film gate comprises an apertured plate 201 from one end of which a plurality of ears 203, supporting a hinge-pin 205, project. A plurality of shoes 207, bent in pairs from metallic strips 209 and supported on a plate 211 pivotally mounted on the hinge-pin 205, are situated on both sides of the aperture 213 and are urged into engagement with the film 141 by a flat spring 215, also supported on the plate 211.

110 A coil spring 217, centrally situated on the hinge-pin 205, and having its ends 219 bent over to engage the shoe-plate 211, resiliently urges the shoe-plate towards the apertured plate 201. It is seen that the gate is normally in closed position.

115 The projection lamp 221 is situated on the same side of the casting as the motor 15. The light from its filament is gathered by a condensing lens mounted in a cavity in the casting and is deflected through an angle of 90° by a mirror 120 223 supported on the main casting 1. It then enters a cavity 13, in the projection head 135, passes between the blades of a light cutter (not shown), centrally situated on the upper horizontal shaft 119, and passes out through an opening in the 125 cover of the cavity to illuminate the film situated adjacent to the aperture 213.

130 The illuminated film is, in turn, focused on a screen by a projection lens 225 supported on a bracket 227 mounted on the cover of the shutter-cavity 13.

135 Although we have shown and described a certain specific embodiment of our invention, we are fully aware that many modifications thereof are possible. Our invention, therefore, is not to be restricted except insofar as is necessitated by the prior art and by the spirit of the appended claims.

We claim as our invention:

1. In an acousto-cinematographic apparatus of the type including a sound reproducer incorporating a turn-table and a motion picture projection system, a shaft secured to said turn-table for rotating said turn-table, a sleeve supported on said shaft, rotatable therewith but longitudinally slidably relative thereto, a drive shaft, another sleeve supported on said first-named shaft and rotatable relative thereto, still another shaft coupled to the elements of said motion-picture projection system to drive said elements, means for coupling said last-named shaft to said drive 150

shaft to drive said last-named shaft, means for coupling said last-named sleeve to said last-named shaft to rotate said sleeve and means for coupling said first-named sleeve to said last-named sleeve to drive said turn-table in synchronism with said projection system.

2. In acousto-cinematographic apparatus of the type including a sound reproducer incorporating a turn-table and a motion picture projection system, a shaft secured to said turn-table for rotating said turn-table, a sleeve supported on said shaft rotatable therewith but slideable longitudinally relative thereto, another sleeve supported on said shaft rotatable relative thereto, a drive shaft, means for coupling said drive shaft to said last-named sleeve to rotate said sleeve, means for coupling said first-named sleeve to said last-named sleeve to drive said first-named sleeve thereby to drive said turn-table independently of said motion picture projection system, still another shaft coupled to said picture projection system to drive said projection system, still another sleeve supported on said first-named shaft and rotatable relative thereto, means coupled to said drive shaft for driving said last-named shaft, means for coupling said last-named sleeve to said last-named shaft to drive said last-named sleeve from said last-named shaft and means for coupling said first-named sleeve to said last-named sleeve to drive said first-named sleeve thereby to drive said projection system.

3. In acousto-cinematographic apparatus of the type including a sound reproducer incorporating a turn-table and a motion picture projection system, a shaft secured to said turn-table for rotating said turn-table, a sleeve centrally supported on said shaft rotatable therewith but slideable longitudinally relative thereto, another sleeve supported near one terminal of said shaft rotatable relative thereto, a drive shaft, means for coupling said drive shaft to said last-named sleeve to rotate said sleeve, means for coupling said first-named sleeve to said last-named sleeve to drive said first-named sleeve thereby to drive said turntable independently of said motion picture projection system, still another shaft coupled to said picture projection system to drive said projection system, still another sleeve supported on said first-named shaft near the other terminal thereof and rotatable relative thereto, means coupled to said drive shaft for driving said last-named shaft, means for coupling said last-named sleeve to said last-named shaft to drive said last-named sleeve from said last-named shaft, and means for coupling said first-named sleeve to said last-named sleeve to drive said first-named sleeve thereby to drive said projection system in synchronism with said turn-table.
